SYNCHRONIZED PULSE GENERATOR

Maurice Moïse Levy, London, England, assignor,
by mesne assignments, to International Standard Electric Corporation, New York, N. Y., a corporation of Delaware

Application March 15, 1944, Serial No. 526,605
In Great Britain April 28, 1943

3 Claims. (Cl. 250—36)

1

The present invention relates to the improvement of electric relaxation oscillators, multivibrators, and like generators of periodic wave forms, and in particular to improved frequency dividing arrangements in which a periodic wave generator is synchronized on a submultiple of a controlling frequency.

It is well known that multivibrators and similar devices are liable to be unstable when synchronized on a submultiple frequency, particularly when the submultiple is of high order. They tend to jump from one frequency to another as a result of small changes in the operating conditions. For this reason it has hitherto not been practicable to use in frequency dividers a step-down ratio greater than about 3 in one stage; and this often necessitates the use of a large number of stages in tandem.

Various arrangements have been proposed for improving the stability of multivibrators; for example, feedback arrangements through resonant circuits tuned to the submultiple frequency; but such arrangements are still found to be limited to a step-down ratio of about 10. The present invention enables the step-down ratio to be still further increased, and the circuit does not become more difficult to synchronize as the step-down ratio becomes larger.

According to the invention, therefore, there is provided a circuit for generating periodic electric waves adapted to be synchronized at a frequency which is a given submultiple of the frequency of controlling waves applied to the circuit, comprising means for generating unidirectional synchronizing pulses repeated at the given submultiple frequency, and means controlled jointly by the said pulses and the controlling waves for generating the said periodic electric waves.

The invention may also consist in a circuit for generating periodic electric waves of saw-tooth form and for synchronizing them on a submultiple of the frequency of a controlling wave, comprising means for deriving from the saw-tooth waves a train of unidirectional synchronizing pulses repeated at the submultiple frequency, and means for applying the pulses and the controlling wave simultaneously to the generating circuit.

In another form the invention provides a multivibrator circuit for generating a train of unidirectional electric pulses repeated at a given frequency and synchronized on a submultiple of the frequency of a controlling wave, comprising means for deriving from the circuit a train of synchronizing pulses repeated at the given fre-

2

quency, and means for applying the synchronizing pulses together with the controlling wave to synchronize the multivibrator circuit.

The invention will be described with reference to the accompanying drawings in which:

Fig. 1 is a diagram used to explain the principle of the present invention;

Fig. 2 shows a schematic circuit diagram of a relaxation oscillator synchronized according to the invention;

Fig. 3 gives diagrams used in explaining the action of Fig. 2;

Fig. 4 shows a schematic circuit diagram of a multivibrator synchronized according to the invention; and

Fig. 5 is a diagram used to explain the action of Fig. 4.

The method of dealing with the difficulty according to the present invention is shown in Fig. 20. 1. The negative grid bias voltage provided by the battery B_2 is increased so that the striking voltage is also increased. Short duration unidirectional pulses are derived from the saw-tooth waves and are delayed and mixed with the control wave and applied to the terminals 1, 2. The sign of the pulses is chosen so that they momentarily reduce the negative bias applied to the control grid. The effect of the striking voltage curve is shown in Fig. 1. It will be seen that the pulses depress every tenth loop of the control wave so that the upward slope of the saw-tooth wave can make contact therewith. If the amplitude of the synchronizing pulses is chosen so that contact is made approximately at the 25 centre of the flank of the controlling wave as shown, that is, when the voltage of the wave is passing through zero, then considerable variation of the operating voltage or amplitude of the controlling wave is allowable before control is lost, and the adjacent loop of the control wave is 30 out of the way and therefore cannot intercept the saw-tooth curve. It is to be noted also that a variation in the amplitude of the controlling wave does not appreciably affect the synchronizing, since the location in time, and height 35 above the time axis, of the centre point of the flank of the wave remains constant as the amplitude varies, the height above the axis being determined by the height of the pulse.

40 The duration of the pulse is not of critical importance; it should preferably be about equal to the period of the controlling wave, but it should not be much greater, otherwise part of the adjacent loop may be depressed into the path of the saw-tooth wave and may be a source of in-

stability if, for instance, the slope of the saw-tooth curve varies.

It will be evident that since only one particular loop of the controlling wave selected by the pulse can be effective in synchronizing the saw-tooth wave, there is no reason for the stability to get worse as the order of the synchronizing submultiple increases.

As will be explained later, the pulse which causes the discharge of the condenser C_1 , in Fig. 2, thereby producing the fly-back stroke, is derived after a definite delay from the preceding fly-back stroke of the saw-tooth wave. So long as the delay is approximately correct, the desired result will be obtained, and errors in the time spacing of the pulses do not accumulate.

Fig. 2 shows one arrangement according to the invention, in which the synchronizing is carried out by the method described with reference to Fig. 1. The circuit for producing the saw-tooth waves is of the relaxation oscillator type and comprises a gas filled valve V_1 having a condenser C_1 connected between the anode and the cathode, a bias source being represented by the high tension source HT and a resistance R_1 connected between the anode and the positive terminal of source HT . The control grid of the valve is connected to a grid biasing battery B_2 through the secondary winding of the transformer T . Condenser C_1 charges up through resistance R_1 until its potential reaches the striking potential of the valve and is then practically instantaneously discharged until its potential is reduced to the extinguishing potential of the valve. The valve V_2 is arranged as a simple pulse generator which is excited by the saw-tooth waves obtained through condenser C_2 from a tapping on the resistance R_1 . The control grid of V_2 is connected to the cathode through two series resistance R_2 and R_3 and a battery or other source B_3 adapted to apply a positive potential to the control grid. The resistance R_5 should be a relatively high resistance adapted to ensure that the positive grid potential is small.

The point on R_1 to which the condenser C_2 is connected should be chosen so that the sudden reduction in the voltage applied to the control grid of V_2 which occurs at the fly back stroke of the saw-tooth wave is sufficient to block the valve. The condenser C_2 becomes charged at the same time, and discharges through the resistance R_2 and the lower portion R_6 of R_1 . If the time constant $C_2 \cdot (R_2 + R_6)$ is small compared with the time constant $C_1 \cdot R_1$ of the relaxation circuit, then the grid potential of V_2 will quickly rise until the valve is unblocked and anode current begins again to flow. Thus the anode potential of V_2 suddenly rises to a maximum on the occurrence of the fly-back stroke, and then remains constant for a short period determined by the time constant $C_2 \cdot (R_2 + R_6)$, and then falls to the original value again, producing very nearly rectangular pulses across the anode resistance R_4 . In Fig. 3 curve a shows the saw-tooth waves and b the voltage pulses obtained across the resistance R_4 . These pulses are applied through a blocking condenser C_3 to the input terminals of the delay network, the output terminals of which are terminated with a resistance R_5 . The upper terminal of R_5 is connected by the conductor x back to the control grid of the valve V_1 through the biasing battery B_2 and the secondary winding of the transformer T .

Delayed pulses will be obtained at the output of the delay network as shown in Fig. 3, curve c . The nth pulse of c is delayed with respect to the nth pulse of b by a time T_1 which is very slightly

shorter than the desired period T of the saw-tooth waves, so that the $(n + 1)^{\text{th}}$ fly-back stroke of the saw-tooth wave occurs approximately at the centre of the nth delayed pulse. The delay T_1 can be obtained by appropriate design of the delay network.

The duration of the pulses b and c can be controlled by adjusting the time constant $C_2 \cdot (R_2 + R_6)$, which may be done by varying any or all of the components C_2 , R_2 and R_6 .

It should be mentioned that the battery B_3 is not essential and may be omitted. The circuit will operate in this case in very nearly the same way; the grid of V_2 will, however, be slightly negative instead of slightly positive in the intervals between the pulses.

This battery may, however, be used to control pulses generated in a different way. In this case the time constant $C_2 \cdot (R_2 + R_6)$ should be made very small so that the coupling circuit will not have any appreciable effect on the pulses. The voltage of the battery B_3 is chosen so that the fly-back stroke of the saw-tooth wave takes the control grid of V_2 only slightly beyond the cut-off. The immediately following rising slope of the saw-tooth wave will very soon unblock the valve, generating pulses similar to those shown at b in Fig. 3. The duration of these pulses is determined by the voltage of the battery B_3 . It will be evident, of course, that any other more convenient type of biasing source may be used in place of the battery B_3 .

One preferred form of the delay network consists of an artificial non-dissipative transmission line which may be made up of a number of low-pass filter sections comprising series inductances and shunt condensers, adjacent inductances being preferably mutually coupled. The sections should be chosen to be sufficiently short so that a high cut-off frequency is obtained, in order not appreciably to deform the pulses. Such an artificial line is very convenient because the delay is substantially independent of frequency over a wide range, and if means is provided for tapping off at any section of the filter, a delay adjustable over a wide range may be obtained. If such a delay network is used, the resistances R_4 and R_5 should be adjusted so that the network is terminated at both ends by its characteristic impedance, in order to avoid reflections of the pulses at the terminals.

The pulses generated by the methods already described will be slightly trapezoidal in form on account of the slope of the trailing edges resulting from the discharge curve of the condenser C_2 (or from the upward slope of the saw-tooth waves). By a slight modification of the arrangement of Fig. 2, truly rectangular pulses can be obtained. In this modification shown in Fig. 2a the conductor x is removed, and the connection back to the control grid of V_1 is taken instead through the connection y to an adjustable tap t at some intermediate point of the delay network. The resistance R_5 should also be short-circuited as shown. The grid battery or other source B_3 should preferably in this case bias the grid negatively as shown in Fig. 2a.

The time constant $C_2 \cdot (R_2 + R_6)$ should be adjusted to be rather larger than before, so that the duration of the pulses generated by the valve V_2 is not much smaller than the period of the saw-tooth wave. Such pulses are shown at d in Fig. 3. These pulses are transmitted through the delay network and reach the tap t after a time T_1 slightly less than the period of the saw-tooth

wave, as shown at *e*. The pulses continue to the short circuited end, where they are reflected with an inversion and return to the tap *t* after a further short period T_2 , as shown at *f*. They continue back to the input end of the delay network where they are absorbed without reflection, the network being properly terminated by R_4 as already explained.

Curve *g* of Fig. 3 shows the resultant effect at the tap *t*. Short rectangular upwardly directed pulses are obtained by the superposition of the two series of pulses *e* and *f*, each pulse being preceded by a downwardly directed V-shaped pulse. This latter pulse could be removed by amplitude limitation or in any other way if desired, but its presence is not harmful, since the effect will be only to raise momentarily the striking voltage of the valve V_1 at a time when it is not required to strike.

It will be evident from the above explanation that the duration T_2 desired for the pulses is obtained by arranging the tap *t* at a distance from the short-circuited end corresponding to $T_2/2$. The delay period T_1 which will be approximately equal to $T - T_2/2$ gives the distance between the input terminals of the network and the tap *t*. In practice it will be found convenient to provide an adjustable short-circuiting switch (not shown) by which the network may be short-circuited at any desired intermediate point. By this means both the times T_1 and T_2 can easily be selected for a variety of conditions.

In Fig. 2, an output terminal 5 is shown connected to a variable tap on the resistance R_1 . The synchronized saw-tooth waves may be obtained from this terminal. Alternatively rectangular pulses similarly synchronized may be obtained from the terminal 6 connected to the lead by which the pulses are conveyed to the grid of V_1 .

Although an arrangement in which synchronization is on a submultiple of order 10 has been used for illustration, the invention is applicable to any submultiple. The theoretical lower limit is order 2, but synchronization by known methods is adequate up to about 3. There is no reason for setting an upper limit to the order of the synchronizing submultiple except that the time T_1 will increase with the order and thus increases the bulk of the delay network, so that by the time the 40th order, for example, is reached, this network may have become rather cumbersome. The stability of the arrangement, however, does not become appreciably worse as the order increases. It should be emphasized that while by any of the known methods the limit is about the 10th order, the present invention is practicable and convenient at least up to the 30th order.

The particular arrangement of Fig. 2 which has been described as an example, is however, only one rather simple form of the invention. In essentials, it comprises a relaxation oscillator represented by the valve V_1 , a pulse generator represented by the valve V_2 and means represented by the delay network for obtaining delayed pulses which are fed back to the relaxation oscillator together with the controlling wave, and are applied to some element of that oscillator whereby its frequency may be controlled and synchronized on the desired submultiple of the controlling frequency.

The same principles may also be applied to synchronizing a multivibrator circuit on a submultiple of the controlling frequency. In Fig. 4

is shown a modification of one well known form of a multivibrator comprising two valves V_3 and V_4 having their control grids and anodes cross-connected through condenser-resistance circuits C_7 , R_7 and C_8 , R_8 . The resistances P are appropriate anode current supply resistances, and the grids are negatively biased by suitable means represented by batteries B_8 and B_9 .

Connected in series with the resistance R_8 (which is the one which is concerned in defining the frequency of repetition) is the secondary winding of a transformer T through which the controlling wave is applied, and a resistance R_9 shunted by two delay networks $DN1$ and $DN2$. These networks are used for generating synchronizing pulses which operate similarly to those previously described. Ignoring these pulses for the moment, it will be understood that the synchronizing wave will be superposed as "ripples" on the dotted curve *d*, and every third ripple, for example, will cross the line V_c , thereby determining the time at which the next pulse is emitted. Since, however, the slope of the curve *d* is so small, the arrangement will be unstable for submultiples of high order. If, however, the synchronizing ripple is superposed on the top of a pulse, it will be raised up out of the way of the preceding ripples and the arrangement becomes stable. This can be seen from Fig. 5 which shows when the synchronizing wave and pulse are supplied. In Fig. 5, the full line represents the actual variation of the grid voltage.

The negative grid bias voltage produced by B_8 is first of all increased, so that the dotted discharge curve *d* would occupy the position shown in the absence of the synchronizing waves. The leading edge *f* of the synchronizing pulse is timed to occur slightly before the time when the generated pulse is to be emitted, and its duration should be about equal to one period of the synchronizing wave. One loop of the wave is thus raised up so that it cuts the line V_c causing the generated pulse to be emitted. The leading edge of this pulse is shown at *a*. As described in connection with Fig. 2, the pulse amplitude should preferably be chosen so that synchronization occurs at the centre of the flank of the wave.

It will be evident that the synchronizing pulse and waves will be superposed on the grid voltage pulse of which *a* is the leading edge. If desired, therefore, it may be arranged so that the amplitude of this grid voltage pulse is sufficiently great to ensure that after the synchronizing pulse has disappeared, the superposed ripples do not bring the grid voltage below the line V_a at any time before the emitted pulse disappears, so that this emitted pulse may not be distorted by the synchronizing wave.

The synchronizing pulse for the $(n+1)^{th}$ pulse is obtained from the nth pulse by reflection in the delay network $DN1$ whose output terminals are left open as shown. In this way the nth pulse which is generated across the resistance R_9 , is reflected back without an inversion, as desired. The total delay suffered by the reflected pulse in $DN1$ should be a little less than the repetition period T desired for the generated pulses. The network $DN2$ has its output terminals short-circuited in order to obtain an inverted reflected pulse delayed slightly longer than the pulse reflected in $DN1$, so that the combination of the two reflected pulses may produce a short synchronizing pulse in a manner similar to that described with references to the curves *d* to *g* of

Fig. 3. If the duration of the synchronizing pulse is to be T_2 , then network DN2 should delay the reflected pulse by a time which is greater than T_2 than the total delay in DN1.

It may be added that the network DN2 is not essential and can be omitted, in which case the synchronized pulse will have the same duration as the emitted pulse. This will operate satisfactorily since the synchronizing pulse will have disappeared before the emitted pulse is due to disappear.

It is to be noted that the resistance R_9 should be chosen so that the networks are correctly terminated, in order to avoid any further reflections of the pulses at the input terminals of the networks.

In the embodiments of the invention which have been described, each cycle of the generated wave is synchronized by a pulse derived from the immediately preceding cycle. Actually the synchronizing pulse could have been derived from any other previous cycle by appropriately increasing the delay introduced by the networks.

The following characteristics of the synchronizing arrangement of the invention may be noted:

1. The delay network determines at which submultiple of the control frequency the relaxation oscillator or multivibrator device is to oscillate. As the delay can be very precisely chosen and is substantially invariable, the arrangement is very stable and is practically unaffected by variation of the operating conditions. Either it oscillates at the chosen submultiple frequency, or not at all. In theory any submultiple may be chosen, the practical limit being determined by the physical dimensions of the network, and being probably somewhere about the 40th order.

2. From Fig. 1 it can be seen that synchronizing will occur so long as the upward slope of the sawtooth wave meets the synchronizing wave somewhere on the descending flank. This means that for a given setting of the delay network, the control frequency f_c may vary within the limits

$$f_c \left(1 \pm \frac{1}{4n} \right)$$

where n is the order of the submultiple employed. Thus the allowable variation for f_c is $\pm 2\frac{1}{2}\%$ for the 10th submultiple and $\pm 1\frac{1}{4}\%$ for the 20th submultiple.

3. The range of synchronization is practically independent of the amplitude of the synchronizing wave, so that the circuit does not have to be readjusted if the control voltage changes. In known arrangements the synchronization range increases with the control voltage but is always smaller than the range possible with the arrangement according to the present invention.

4. The parameters such as the power supply voltages and control voltage which do not substantially affect the shape of the waves can vary within wide limits which are independent of the order of the submultiple employed.

5. The parameters which do affect the wave shape, such as the values of the timing resistances and condensers, can also vary within wide limits, which however are inversely proportional to the order of the submultiple employed.

The multivibrator described with reference to Fig. 4 is a simplified form of only one possible type to which the invention is applicable. The same principles may be applied in numerous other like cases.

What is claimed is:

1. A circuit for generating periodic electric waves of sawtooth form and for synchronizing them in a submultiple of the frequency of a controlling wave comprising a relaxation oscillator for generating said sawtooth waves, a pulse generator for converting the waves into unidirectional synchronizing pulses at the submultiple frequency, a delay network connecting the pulse generator to the oscillator for applying the pulses thereto and means for applying said controlling wave to said oscillator simultaneously with said pulses.

2. An arrangement for generating periodic electric waves of saw-tooth form and for synchronizing them on a sub-multiple of the frequency of a controlling wave, a relaxation oscillator for generating the saw-tooth waves said oscillator comprising a gas-filled triode having a control grid, and arranged periodically to discharge a condenser, a pulse generator for deriving from the saw-tooth waves themselves a train of unidirectional synchronizing pulses repeated at the sub-multiple frequency, a delay network for delaying the said synchronizing pulses by a time interval slightly shorter than the period of the saw-tooth waves, and means to apply the pulses from the delay network together with the controlling wave simultaneously to the control grid of said triode.

3. An arrangement according to claim 2 in which the said delay network is short-circuited at a point remote from its input terminals and the said delayed pulses are tapped off from a point intermediate the said input terminals and the said short circuit point.
